UNITED STATES PATENT OFFICE.

DAVID R. STEELE, OF BALTIMORE, MARYLAND, ASSIGNOR OF ONE-HALF TO HARRY D. HARVEY, OF BALTIMORE, MARYLAND.

FURNACE-TILTING MECHANISM.

No. 900,043.

Specification of Letters Patent.

Patented Sept. 29, 1908.

Original application filed October 12, 1905, Serial No. 282,452. Divided and this application filed March 1, 1906.
Serial No. 303,725.

To all whom it may concern:

Be it known that I, DAVID R. STEELE, a citizen of the United States, residing at Baltimore, in the State of Maryland, have invented certain new and useful Improvements in Furnace-Tilting Mechanism; and I do hereby declare the following to be a full, clear, and exact description of the invention, such as will enable others skilled in the art to which it appertains to make and use the same.

This invention relates to improvements in furnace structures, and particularly to smelting furnaces, which are adapted for smelting or reducing ores and then pouring them in a molten condition.

It is the object of the invention among other things, to provide a furnace with a tilting or tipping body portion and mechanism for tipping the same.

With these and further objects in view, the invention comprises certain novel constructions, combinations and arrangements of parts as will be hereinafter fully described and claimed.

In the accompanying drawing,—Figure 1 is a side elevation of a smelting furnace the cover or top thereof being in position and provided with my improved lifting means. Fig. 2 is a side elevation of the gearing used in controlling the movement of the furnace, the long wheel for operating the same being also shown.

In the accompanying drawing 1 indicates a furnace which is generally pivotally mounted on suitable supports as 2, the furnace being preferably of the open top type adapted for the pouring of metals after they have been smelted within the furnace. It is necessary in carrying on some operations to close or partially close the top of the furnace in order to retain and properly apply the heat employed to the contents of the furnace. For this purpose a cover or top of material capable of withstanding a considerable degree of heat without melting or without detriment is employed and so mounted that it may be used without interfering with the tipping of the furnace. I preferably construct such a cover or top of fire brick as at 3, and secure the same for lifting purposes by means of a band or ring 4, which is drawn tightly around the periphery of said fire

brick, the said band usually fitting in an annular groove in the edge of the cover.

In the operation of the device the cover 55 may be lifted from its closed position as shown in Fig. 1 by grasping the end of the lever 17 and pulling it downwardly to an approximately horizontal position. This will straighten the toggle connection formed by 60 the arm 19 and the link 20 forcing the sleeve 6 upwardly and thus lifting the cover well out of engagement with, and above the upper edge of the furnace 1. The cover thus being moved entirely out of the way of the 65 furnace 1 the said furnace may be readily tipped upon its supports for pouring molten metal or emptying the contents thereof.

In connection with the cover, means is employed for holding the furnace proper in an 70 upright position or for tilting it to any angle necessary for the pouring of molten metals and such mechanism forms an important feature of the invention. The body portion of the furnace is preferably constructed 75 with a cylindrical closure as indicated at 1 having trunnions projecting upon the opposite sides thereof to engage the bearings in the standards or supports 2. Secured to one of said trunnions is a gear 24 which meshes 80 with a similar gear 25 rigidly secured to the outer end of a short shaft 26. The inner end of said short shaft 26 carries a gear 27 which in turn meshes with the comparatively small pinions 28. The pinion 28 is rigidly secured 85 to the inner end of the shaft 29 journaled in one of the standards 2. The outer end of the shaft 29 projects beyond the standard and beyond the gearing a sufficient distance to carry a hand wheel or turning device made 90 up of a hub 30 having radiating handle arms 31. The said handle arms are screwed into sockets formed in the hub 30 and fastened by means of binding nuts 32 so as not to turn or twist out of place. The outer ends of said 95 arms 31 are bent to one side to form hand holds 33. The leverage thus obtained through the arms 31 and the train of gears described is such that the furnace can be easily turned upon its trunnions and held in 100 any of its adjusted positions. The upper part of the furnace is provided with a pouring spout as at 34 while the lower portion of the furnace has a slag opening 35 through

which the slag may be removed from the furnace from time to time. The furnace is also provided with an opening in its wall as at 36 opposite which a burner 37 is mounted, the 5 said burner being capable of injecting oil under air or steam pressure into the furnace, where it is burned for heating the same.

When the contents of the furnace have been subjected to heat a sufficient length of 10 time and it is desired to pour the contents into a mold or other receptacle the cover 3 is elevated by pulling upon the lever 17, and is then turned to one side after which the furnace is tipped by means of the hand wheel 15 and the gearing until the material is run into a dipper for pouring. The furnace is capable of being held by the gearing with a minimum of exertion in any of its adjusted positions, and as above stated, the cover also 20 requires an exceedingly small expenditure of force or strength to accomplish its lifting, and turning to one side.

This is a divisional application of my ap-

plication for furnaces, filed October 12, 1905, Serial No. 282,452, and is made a separate 25 application.

Having now described my invention, what I claim as new and desire to secure by Letters Patent is:—

The combination of a furnace body, trunnions thereon, standards supporting said trunnions, a train of gearing connected with one of the trunnions, the wheels of said gearing mounted on the trunnion last mentioned and on an adjoining standard, means for 30 operating the gearing, a furnace cover, an upright carried by said last-mentioned trunnion, and a cover-operating device carried by the upright.

In testimony whereof I affix my signature 40 in presence of two witnesses.

DAVID R. STEELE.
